UNITED STATES PATENT OFFICE.

CLARENCE W. LOWE, OF CHICAGO, ILLINOIS, ASSIGNOR OF ONE-HALF TO ROBERT WALLACE, OF CHICAGO, ILLINOIS.

CURTAIN-POLE SUPPORT.

1,115,949.

Specification of Letters Patent.

Patented Nov. 3, 1914.

Application filed April 13, 1914. Serial No. 831,510.

To all whom it may concern:

Be it known that I, CLARENCE W. LOWE, a citizen of the United States, residing at Chicago, in the county of Cook and State 5 of Illinois, have invented certain new and useful Improvements in Curtain-Pole Supports, of which the following is a specification.

This invention relates to supports for curtain poles and its object is to provide in 10 connection with a device of this kind novel and improved means for elevating the curtain pole to its seat and for disengaging the pole and lowering the same.

15 In order that the invention may be better understood, reference is had to the accompanying drawing, in which—

Figure 1 is a front elevation showing the 20 application of the invention, and Fig. 2 is a side elevation thereof.

Referring specifically to the drawing, 5 denotes a pole designed to hold a curtain, the latter not being shown. The pole is supported at its ends by brackets, each of which 25 latter comprises a metal strip 6 having a doubled intermediate portion 7 which is bent outward and upward to form a seat for the pole. The strip has perforations to receive screws or other fastenings 8 whereby 30 it is secured to the window frame or other part. One part of the doubled portion of the strip extends in a curve from the main body of the strip, as indicated at 9, on which curved portion the pole seats, and the 35 other part of the doubled portion extends downward at an inclination, as indicated at 10, to the bottom portion of the strip. Above the curved seat 9 the two doubled portions extend upward and outward at an 40 inclination. The strip 6, near its upper end, carries a bracket 11 in which is journaled a pulley 12 over which passes a hoisting line 13. One end of this line extends downward from the pulley and is made fast to 45 the pole 5, and the other end of the line extends downward in a loop and is also made fast to the pole. Thus, it will be seen that a pull on the looped end of the line lifts the pole out of the seat 9, and upon 50 releasing the line, the pole lowers. By this operation the pole may also be elevated. Both ends of the pole are provided with a hoisting device. The seat 9 is provided with a guard 14 for retaining the pole 5. This

guard comprises a looped wire which is pivoted to the strip 6, above the pole seat, as indicated at 15. The length of the loop is such that its free end normally rests on the extremity of the parts 7 and projects outward a short distance therefrom. 55

When the pole 5 is hoisted as hereinbefore described, it will swing the guard 14 upward upon striking the same, as shown by dotted lines in Fig. 2. The pole is elevated until it slips past the free end of the 60 guard, whereupon the latter drops down back to its normal position, in which position it is inclined downward from the strip 6. The pole may now be lowered, and it will clear the parts 7 by sliding down the 65 guard. When the pole is being elevated to its seat and it reaches the incline 10, it slides upward along the same until it strikes the projecting end of the guard, whereupon the guard is swung upward, and when the 70 pole clears the outer end of the parts 7 and the hoisting line 13 is released, the pole drops into the seat 9 back of the parts 7, and the guard drops down to its normal position. The action of the guard is therefore 75 entirely automatic, and the pole can be raised or lowered by simply operating the line 13.

I claim:

1. The combination with a curtain pole; 80 of a seat for the pole having an upstanding part in front thereof, a pivoted guard member above the seat, said member normally seating on the extremity of the upstanding part and projecting therefrom, and a hoisting 85 device connected to the pole.

2. The combination with a curtain pole; 90 of a seat for the pole having an upstanding part in front thereof, a pivoted guard member above the seat, said member normally 95 seating on the extremity of the upstanding part and projecting therefrom and when thus seated having an upward inclination from the upstanding part, and a hoisting device connected to the pole.

3. The combination with a curtain pole; 100 of a seat for the pole having an upstanding part in front thereof and an incline leading to said part, a pivoted guard member above the seat, said member normally seating on 105 the extremity of the upstanding part and projecting therefrom, and a hoisting device connected to the pole.

4. The combination with a curtain pole; of a supporting bracket having a seat for the pole, and inclines above and below the seat, the incline above the seat being pivoted and having its free end extending past the lower incline, and a hoisting device connected to the pole.

In testimony whereof I affix my signature in presence of two witnesses.

CLARENCE W. LOWE.
